UNITED STATES PATENT OFFICE.

JUSTIN THARAUD, OF WEEHAWKEN, NEW JERSEY.

DESIGN FOR A DISH OR SIMILAR ARTICLE.

58,515.

Specification for Design.

Patented July 26, 1921.

Application filed February 25, 1921. Serial No. 447,889. Term of patent 14 years.

To all whom it may concern:

Be it known that I, JUSTIN THARAUD, a citizen of the United States, residing at No. 438 Palisade avenue, Weehawken, in the county of Hudson, State of New Jersey, have invented a new, original, and ornamental Design for a Dish or Similar Article, of which the following is a specification, reference being had to the accompanying drawing, forming part thereof.

The figure is a plan view of a quarter section of a dish showing my new design.

I claim:

The ornamental design for a dish or similar article, as shown.

JUSTIN THARAUD.
